Claims priority, application Canada May 11, 1961

Term of patent 14 years

(Cl. D54—2)

FIGURE 1 is a plan view of a knurled wire showing my new design;

FIGURE 2 is a side elevation of the knurled wire shown in FIGURE 1;

FIGURE 3 is a cross-sectional view along the line 3—3 of FIGURE 1.

The wire is circular in cross-section and the grooves and projections thereon repeat around the periphery thereof as best shown in FIGURE 3.

I claim:

The ornamental design for a knurled wire, as shown and described.
